HENRY WEBER, OF CHICAGO, ILLINOIS, ASSIGNOR TO LATHAM MACHINERY COMPANY,
OF CHICAGO, ILLINOIS, A CORPORATION OF ILLINOIS.

WORK-SUPPORT FOR STAPLING-MACHINES.

1,175,029.

Specification of Letters Patent.

Patented Mar. 14, 1916.

Application filed December 24, 1914. Serial No. 878,851.

To all whom it may concern:

Be it known that I, HENRY WEBER, a citizen of the United States, residing at Chicago, in the county of Cook and State of Illinois, have invented certain new and useful Improvements in Work-Supports for Stapling-Machines, of which the following is a specification.

This invention relates to work supports for stapling machines for boxes, cartons and other articles, and consists substantially in the combination and arrangement of the parts hereinafter described, illustrated in the accompanying drawings and more particularly set forth in the appended claims.

In the drawings, Figure 1 is a front elevation of the invention as applied to one form of stapling machine; Fig. 2 is a side elevation of the invention applied to the same form of stapling machine; Fig. 3 is a side elevation, with parts broken away, of the movable support; Fig. 4 is a section on line 4—4 of Fig. 3; Fig. 5 is a side elevation, with parts broken away, of another form of stapling machine with this invention applied thereto; Fig. 6 is an enlarged section on line 6—6 of Fig. 5; Fig. 7 is a fragmentary top plan view of the staple clenching mechanism shown in Fig. 6, and Fig. 8 is a detail section on line 8—8 of Fig. 5.

Referring first to Figs. 1 to 4 inclusive, of the drawings, the numeral 1 designates a frame or standard of a stapling machine of any well known or suitable type, such as for example, as that shown in my prior Patents 665,946 and 548,681. Carried by the standard 1 is a laterally projecting arm 2 carrying a staple forming and driving head 3 and spool 4. The stapling head 3 comprises any suitable mechanism for feeding wire from the spool 4 forming it into staples and driving the staples downwardly through the work shown at 6 in Figs. 1 and 2. As stapling devices for this purpose are old in the art and specifically form no part of my present invention, further description of these parts is unnecessary. Extending through a standard 1, as shown more clearly in Fig. 3, is a bar or shaft 7. The shaft 7 is rigidly mounted in the standard and is held in position by a collar 8 and pin 9. Journalled on the shaft 7 is a sleeve 10. Attached to the standard 1 by any suitable means, such as legs or screws 11, is a plate 12. The plate 12 surrounds the shaft 7 and

has a circular bearing 13 projecting from one side thereof forming an additional bearing for the sleeve 10. The sleeve 10 is held from longitudinal movement on the shaft 7 by means of a head 14. A circular flange 15 is formed on the sleeve 10 and this flange is cut away to provide the shoulders 16, shown in Fig. 1. A pin 17 extends from the plate 12 between the shoulders 16 to limit the rotation of the sleeve 10 about the shaft 7. At the lower portion of the sleeve 10 at one end thereof is a projection 18. Rigidly fixed to this projection is a piece of hardened metal 19 having cam surfaces 20 and a latch-opening 21. A latch 22 is adapted to enter the opening 21 to hold the sleeve 10 from rotating. The latch 22 has a bar 23 extending downwardly therefrom and carrying a foot piece 24 for operating the latch. A tension spring 25 is fastened to the bar 23 and the standard 1 and tends to hold the latch in its upper position. Rigidly attached to the sleeve 10 is a work supporting bar 26. This bar 26 extends upwardly from the sleeve 10 and has its upper end 27 in position to coöperate with the stapling head 3 to bend and clench the ends of the staples as they are forced through the work by the stapling mechanism. In the form of device shown in Figs. 3 and 4 the upper end 27 of the arm 26 carries what is called a self stapling member 28. In this member grooves 29 are formed against which the ends of the staples are impinged. The inclination of the grooves is such that the ends of the staples are bent and turned upwardly, due to the force of the blow upon the staple from above. The member 28 may be adjusted to accommodate different thicknesses of work by means of a bolt 30 integral therewith and locknuts 31. With a stationary work support or table, such as has been heretofore used, it has been impossible to staple together the bottom flaps of a carton because the boxes could not be placed in position beneath the stapling head. With the present invention when it is desired to complete a carton by stapling together the bottom flaps the latch 22 is released, permitting the arm 26 to swing to the right, in Fig. 1, far enough to allow the boxes to be slid down over the work supporting bar 26. After the carton has been positioned over the bar 26 so that the top of the bar is in contact with the inside of the bottom of the

carton the bar 26 is swung back into its upright position, the latch 22 automatically springing into place to hold the bar in this position. The bottom flaps may now be 5 stapled together and when the work is complete the operator presses down on the foot piece 24 permitting the bar to be again swung to one side so that the box may be removed. The distance that the bar 26 swings 10 is limited by the pin 17.

It is sometimes desirable to have a positively operating member to bend up the ends of the staples after they have been forced through the work. A machine of 15 this kind with the present invention applied thereto is shown in Fig. 5 of the drawings. In this form of machine the bar 26 has mounted thereon a reciprocating plunger 32. This plunger 32 carries a head 33 which is 20 forced upwardly at proper intervals to contact with the ends of the staples projecting through the work. As the staples are forced through the work they first strike the beveled shoulders 34, shown in Fig. 6, 25 and are bent slightly inwardly. They are then in position to be struck by the head 33 by which the clenching action is completed. The plunger 32 is operated by a lever 35 mounted on a bracket 36 and having one end 30 37 extending into position beneath a rod 38 within the standard 1. The rod 38 is reciprocated by a cam 39 and a spring 40. The end of the lever 35 is bifurcated and the bifurcations 41 are positioned on each 35 side of a lug 42 carried by the plunger 32. The upper and lower surfaces of the lug 42 are arcuate, the center of curvature being the axis of the shaft 7. This formation permits the lug to slide laterally between the 40 bifurcations on the lever 35 as the bar 26 is swung about the shaft 7. Carried by the lug 42 is a horn 43 which serves to guide the bifurcations of the lever 35 back into operative relation with the lug 42 when the bar 45 26 is swung from its inoperative to its operative position.

From the description of the device given above it is believed that the operation will be evident. In forming a carton of card-board or similar material the sides of the carton are first stapled together. In order to form the bottom the end flaps are folded over upon one another and are stapled in this folded position. It is in performing 50 this last stapling operation that the present invention is especially valuable. After the sides have been stapled the operator presses down upon the foot pedal 24 thus releasing the sleeve 10 and the arm 26 which are 55 swung to the right, as shown in broken lines in Fig. 1. The carton is then slid down over the bar 26 until the bottom flaps come in contact with the end of the bar. The end 60 of the bar is then swung back into upright position and is automatically locked into 65

this position by the latch 22. When the stapling operation has been performed the carton may be removed by swinging the bar 26 from under the stapling head in the manner previously described.

70

I claim:

1. In a stapling machine, an upright standard, a stapling head carried by said standard, a shaft rigidly secured to said standard at right angles therewith, a work support pivotally mounted on said shaft and adapted to swing into and out of position to cooperate with said stapling head, means for limiting the movement of said work support in one direction to a position directly beneath the stapling head, means for locking the work support in this position, means for unlocking the work support, and means for limiting the movement of said work support in the other direction. 80

2. In a stapling machine, a standard, a laterally projecting shaft rigidly secured to said standard, a sleeve mounted on said shaft to rotate thereon, a work supporting bar secured to said sleeve and projecting upwardly therefrom, a latch adapted to hold said work supporting bar in a vertical position, and a foot pedal adapted to release said latch and permit said bar to swing laterally out of said vertical position. 90

3. In a stapling machine, a standard, a laterally projecting arm carried at the upper end of said standard, a stapling head secured to the end of said arm, a laterally projecting shaft rigidly secured to said standard beneath said arm, and parallel therewith, and having one end thereof extending beneath said stapling head, a sleeve carried by said shaft and adapted to rotate thereon, a straight work supporting bar secured to said sleeve and projecting upwardly therefrom toward said stapling head, and arranged to move into and out of the plane of said arm and shaft to bring the end of said bar into and out of position beneath said stapling head, means for latching said bar in position with its end beneath said stapling head, and a foot pedal for releasing said latch to permit said bar to swing laterally to bring the end thereof out of position beneath said stapling head to permit work to be operated upon to be slid upon said bar. 110

4. A stapling means comprising a support, a horizontal shaft rigidly secured to said support, a sleeve journaled on said shaft, an arcuate flange on said sleeve, a latch member carried by said flange, a latch on said support co-operating with said latch member, means for releasing said latch, an upright arm carried by said sleeve, and a suitable clenching device carried by said arm at its upper end. 120

5. A stapling machine comprising a support, a horizontal shaft carried by said sup- 130

port, a plate provided with a bearing and surrounding said shaft and secured to the support, a sleeve journaled on said shaft and on the bearing on said plate, an arcuate 5 flange on said sleeve, a latch member carried by said flange, a latch on said plate co-operating with said latch member, means for releasing said latch, means for limiting the relative motion between said flange and 10 said plate, an upright arm carried by said sleeve, and a suitable clenching device carried by said arm at its upper end.

6. In a stapling machine, a standard, an arm extending laterally from said standard 15 and arranged to rotate thereon, an upright bar attached to said arm to oscillate therewith, a plunger mounted on said bar, a lever pivoted on said standard, and an operative connection between said lever and 20 said plunger preventing relative movement of the plunger and lever vertically but permitting them to move laterally relative to one another.

7. In a stapling machine, a work supporting bar adapted to swing about a horizontal pivot, a staple clenching device carried by said bar, means for operating said staple clenching device, and a connection 25 between said clenching device and said operating means for holding the two in operative relation when the supporting bar is

in one position and in inoperative relation when the bar is in another position.

8. In a stapling device, a work supporting bar mounted for oscillation about a 35 pivot, a plunger slideable longitudinally on said bar, a lug carried by said plunger, means arranged to co-operate with said lug to move said plunger and a projection on said lug arranged to guide the plunger operating means into operative connection with the lug after an oscillation of said work support. 40

9. In a stapling device, a work supporting bar mounted for oscillation about a 45 pivot, a plunger slideable longitudinally on said bar, a lug carried by said plunger, means arranged to co-operate with said lug to move said plunger when said bar is in one position, and an arcuate horn carried 50 by said lug to guide said operating means and lug into operative relation with one another when said bar is swung in one direction.

In testimony whereof I have signed my 55 name to this specification, in the presence of two subscribing witnesses, on this 21st day of December, A. D. 1914.

HENRY WEBER.
